ABSTRACT

A method of microbiocidally treating a surface or treating hard water which comprises applying to the surface or admixing with the water microbiocidal quaternary ammonium derivatives of indene, at least some of which retain a high degree of their microbiocidal activity in hard water, the quaternary nitrogen having a long chain alkyl of eight to 18 carbon atoms, but preferably 12 to 14 carbon atoms and two lower alkyl chains of 1 to 4 carbon atoms attached thereto.

2 Claims, No Drawings

BACTERICIDAL QUATERNARY AMMONIUM DERIVATIVES OF INDENE

This is a division of application Ser. No. 857,573, filed Sept. 12, 1969, now U.S. Pat. No. 3,636,115.

This invention relates to a new class of microbiodically active quaternary ammonium compounds, and it particularly relates to quaternary ammonium compounds derived from indene.

Many quaternary ammonium compounds have heretofore been known which were very effective microbiodical agents. However, most of these prior compounds were found to lose a large part of their microbiodical effectiveness when subjected to dilution with hard water. The compounds of the present invention are quaternary ammonium derivatives of indene wherein the quaternary nitrogen has a long chain of eight to 18 carbon atoms and also has two lower alkyls of one to four carbon atoms attached thereto. These compounds are highly microbiodical. Furthermore, those of these compounds which have a long chain of 12 to 14 carbon atoms have been found to be among the relatively few quaternaries which are not only highly microbiodical but which are not deleteriously affected by hard water.

The term "hardwater" is generally used to describe water having at least about 75 p.p.m. of calcium carbonate or equivalent salts. However, naturally occurring water may, and usually does contain such salts in an amount running up to several hundred p.p.m.

In accordance with the present invention, quaternary ammonium derivatives of indene may be prepared through hydrogenation, chloromethylation and reaction with tertiary amines as set forth in the following reaction.

In the above reaction, R is an alkyl group of between 12 and 14 carbon atoms, while R' and R'' are lower alkyls of one to four carbon atoms.

Indene is well known and widely used as a monomer for the preparation of commercial resins. It occurs in the solvent naphtha cuts of coal tar distillates. It is, therefore, an inexpensive and readily accessible raw material for chemical synthesis. This makes the present invention even more valuable because other quaternary ammonium compounds which may have some of the same properties require the use of expensive and difficultly obtainable materials.

The following examples are illustrative of the present invention, but are not intended as limitations thereof except as claimed:

EXAMPLE I

833 grams of crude indene (X-Heavy Solvent b. 172°-188° C.; Neville Chemical Company, Pittsburgh, Pa.), 780 grams of methanol and 7.75 grams of palladium-charcoal catalyst were placed in a hydrogenation vessel. Hydrogenation was accomplished in 8 hrs. at 125°-130° C. at a pressure of about 60 psi. with vigorous stirring. The vessel was cooled and the solution

discharged and filtered to remove the catalyst. Methanol and forerun up to 170° C. were removed by distillation, and material boiling at 170°-176° C. was taken as the product (650 grams). Although the pressure used here was 60 psi., it has been found that a pressure as high as about 500 psi. may be used with the same result.

EXAMPLE II

To a stirred mixture containing 590 grams of indan from Example I, 507 cc of 37 percent formaldehyde and 1,060 cc of conc. HCl, was added 695 cc of conc. sulfuric acid over seven hours. The temperature was held at 60° C. for this period. Stirring was continued for 20 hours. The reaction mixture was then poured into ice water and extracted with ethyl ether. The ether layer was washed twice with 5 percent sodium bicarbonate and once with water. It was then dried overnight over anhydrous sodium sulfate, filtered and then distilled.

Fractions having a boiling point of 120°-140° C. at 8-10 mm were combined to give 420 grams of chloromethyl indan.

EXAMPLE III

Chloromethyl indan was reacted with several alkyl dimethyl amines, as follows:

Alkyl Chain	Chloro-methyl Indan, grams	Chloro-methyl Indan, moles	Alkyl Dimethyl amine, grams	Alkyl Dimethyl amine, moles
n C ₁₀	4.9	0.03	5.6	0.03
n C ₁₂	4.9	0.03	6.6	0.03
n C ₁₄	4.9	0.03	7.7	0.03

35

The chloride and amine were weighed into a 50 ml round bottom flask and an equal weight of isopropyl alcohol added. The mix was refluxed on a steam bath overnight giving < 95 percent conversion to alkyl dimethyl indanyl methyl ammonium chloride in each case.

EXAMPLE IV

The products of Example III were evaluated for Hard Water Tolerance using the AOAC Germicidal and Detergent Sanitizers test method procedure No. 5023 with E. coli ATCC No. 11229.

The results were as follows:

	Product	HWT
(1) Decyl dimethyl indanyl methyl ammonium chloride		< 200
(2) Dodecyl dimethyl indanyl methyl ammonium chloride		1100
(3) Tetradecyl dimethyl indanyl methyl ammonium chloride		700
(4) 70% (2)/30% (3)		900

The Phenol Coefficient for (2) vs. *S. aureus* was determined to be 830; vs. *S. typhosa* — 780.

EXAMPLE V

Reagent grade indan (99percent, supplied by Aldrich Chemical Company, was chloromethylated using the conditions of Example II, and this chloromethyl indan was reacted with C₁₀ and C₁₂ alkyl diethyl amines and C₁₂ and C₁₄ alkyl dimethyl amines as described in Example III.

The products of these reactions were evaluated as described in Example IV with the following results:

	Product	HWT
(5) Decyl diethyl indanyl methyl ammonium chloride		300
(6) Dodecyl diethyl indanyl methyl ammonium chloride		700
(7) Dodecyl dimethyl indanyl methyl ammonium chloride		1100
(8) Tetradecyl dimethyl indanyl methyl ammonium chloride		700

75

By comparing results obtained using products (2) and (3) from Example IV with products (7) and (8) above, it can be seen that the products derived from indan derived from a commercial source without extensive purification are equivalent to those obtained using highly purified indan. This is significant because it obviates the necessity for expensive and time-consuming purification.

The results of microbiocidal activity, as indicated above, show unexpectedly excellent hard water tolerance of the products of this invention since even the adjacent decyl compounds are significantly inferior in this respect.

Instead of chlorine, other halogens such as bromine and iodine may be used as the anion.

The invention claimed is:

1. A method of bactericidally treating a surface which comprises applying thereto a bactericidally effective amount of a compound of the formula:

wherein R is an alkyl group of eight to 18 carbons, R' and R'' are lower alkyls of one to four carbons, and X is a halogen.

2. A method of treating hard water to make it bactericidal which comprises treating said water with a bactericidally effective amount of a compound of the formula:

wherein R is an alkyl group of eight to 18 carbons, R' and R'' are lower alkyls of one to four carbons, and X is a halogen.
